BOX TOP

George Posner, New York, N. Y., assignor to The
 New York Merchandise Co., Inc., New York,
 N. Y., a corporation of New York

Application September 12, 1950, Serial No. 12,157

Term of patent 3½ years

(Cl. D58—12.6)

To all whom it may concern:

Be it known that I, George Posner, a citizen of the United States, and resident of New York city, New York, have invented a new, original, and ornamental Design for a Box Top, of which the following is a specification, reference being had to the accompanying drawing, forming a part hereof.

Figure 1 is a top view of a box top, showing my new design.

Figure 2 is a front view thereof.

Figure 3 is a side view.

The design on the rear and the side not shown are similar to the front and the side shown, respectively. The shaded portions of the drawing not representing plain surfaces are for the purpose of showing contrasting appearance.

I claim:

The ornamental design for a box top, as shown and described.

GEORGE POSNER.
